UNITED STATES PATENT OFFICE

146,990

DESIGN FOR A SHROUD FOR WINDSHIELD WIPER ARM

Theodore J. Smulski, Gary, Ind., assignor to Productive Inventions, Inc., a corporation of Indiana

Application May 12, 1945, Serial No. 119,522

Term of patent 14 years

(Cl. D14—6)

To all whom it may concern:

Be it known that I, Theodore J. Smulski, a citizen of the United States and a resident of Gary, in the county of Lake and State of Indiana, have invented a new, original, and ornamental Design for a Shroud for Windshield Wiper Arm, of which the following is a specification, reference being had to the accompanying drawing, forming part thereof.

Figure 1 is a top plan view of a shroud for windshield wiper arm, showing my new design;

Figure 2 is a side view in elevation of the shroud in Figure 1;

Figure 3 is a bottom view of the shroud; and

Figure 4 is a perspective view of the shroud.

The dotted lines shown in the several figures

of the drawing are for illustrative purposes only.

I claim:

The ornamental design for a shroud for windshield wiper arm, as shown and described.

THEODORE J. SMULSKI.
